UNITED STATES PATENT OFFICE.

MARY TORRENS, OF BRIDGNORTH, ENGLAND.

GLOVE.

SPECIFICATION forming part of Letters Patent No. 720,640, dated February 17, 1903.

Application filed March 27, 1902. Serial No. 100,324. (No model.)

To all whom it may concern:

Be it known that I, MARY TORRENS, a subject of the King of Great Britain, residing at Claverley, Bridgnorth, in the county of Salop,

5 England, have invented certain new and useful Improvements in Gloves; and I do declare the following to be a full, clear, and exact description of the invention, such as will enable others skilled in the art to which it app-

10 pertains to make and use the same.

My invention relates to gloves for protecting the hands while performing domestic and other operations, and has for its object certain improvements whereby great freedom of 15 movement for the hands is permitted while wearing the gloves without lessening the waterproof or protective qualities thereof, a strong non-slipping grip of the articles under treatment is rendered possible, and the 20 usefulness of the gloves is in other ways increased.

In the accompanying drawing I have illustrated a preferred construction of my glove according to my invention.

25 According to my invention I form the gloves with arm extensions A, so that when in use they will protect the wrists and a portion of the arms, and I do away with the usual fastening devices and instead close the

30 gloves entirely, except at the end where the hand is inserted—that is, at the end remote from the finger portions—at which part I provide an elastic band B, which will cause the gloves to fit tightly upon the arm, while per-

35 mitting sufficient extension to allow of the insertion of the hand. Thus it will be seen that the hand, wrist, and a portion of the arm of the wearer are entirely closed in and protected by a glove, and therefore domestic

40 operations—such as the washing up of utensils, scrubbing, clothes-washing, and the like—and also industrial operations which require the hand to be protected or for which that is desirable can be performed without soiling

45 of the hands. The elastic band B upon the arm will largely prevent any liquid passing

to the inside of the glove. Any other appropriate fastening device, however, may be employed at this end or there may be no fastening at all.

50 The gloves are of waterproof or other protective materials of a flexible nature and are suitably lined, so that great freedom of movement of the hands in wearing the gloves is permitted, and it is therefore possible to obtain a strong grip of articles under treatment without risk of dropping them owing to an imperfect and awkward grip of them, as happens now without the use of this invention. 55 To further obtain a non-slipping grip upon the articles, I prefer that a waterproof or protective material having a roughened surface or having gripping-strips C of appropriate material be affixed to the surface, so as to provide the necessary roughness.

60 In many domestic operations it becomes necessary at times to employ a stronger and rougher article than the usual dish-clout to remove impurities, and to provide for such an article being handy and ready for use 70 when required I apply a piece of felt or other material D with hooks or eyes E or other fastening devices, and I provide the gloves with the corresponding portions of said fastening devices, so that the piece of material can be 75 secured upon the glove in any suitable position, such as the back or side, when required for rougher use.

65 I claim—

An elastic waterproof glove having the fingers and thumb provided with reinforced roughened strips of material, and an interchangeable piece of material provided with fastenings detachably connected to the back of the glove, substantially as specified.

80 In testimony whereof I have hereunto set my hand in presence of two subscribing witnesses.

MARY TORRENS.
